UNITED STATES PATENT OFFICE.

EDWARD LINDNER, OF NEW YORK, N. Y.

FURNITURE-CASTER.

Specification of Letters Patent No. 31,548, dated February 26, 1861.

To all whom it may concern:

Be it known that I, EDWARD LINDNER, of the city, county, and State of New York, have invented new and useful Improvements in Globe-Casters; and I hereby declare that the following is a full and clear description of the same, reference being had to the accompanying drawing, in which—

Figures 1, 2, 3, 4, 5, 6, 7 and 8, represent 10 views in elevation, section and detail of my invention together with modifications of the same.

The nature of my invention consists in the 15 peculiar construction of the globe containing socket and in the means employed to keep the globe within the socket whereby a cheaper and more durable article is produced while a greater perfection of its operation is attained.

20 In Fig. 1 the socket is made solid with the screw that fastens it with the leg of the table, chair or other furniture to which it is applied. The peculiarity of this socket consists in the formation of the concavity of 25 the socket which is elliptical or oval or otherwise similarly shaped so that the plane of its greatest axis shall coincide with that of the globe, the socket at the same time being in tangential contact with the top of 30 the globe. The opening of the socket at the under side thereof is circular of a diameter somewhat smaller than that of the globe.

To insert the globe within the socket, the latter is heated when, by its expansion it 35 will admit of the globe and imprison it by subsequent cooling and contraction. By this construction of the socket, the globe, when in operation, will have but one point of contact within the socket which is diametrically 40 opposite to that without the socket.

In Fig. 2 the socket and the screw are distinct from each other and may be made of different materials according to the strength required and convenience of manufacture. 45 The socket may be made of brass or other malleable material and is provided with hooks that may be bent inward after insertion of the globe within the socket.

The peculiarity in this caster consists in 50 the oblong shape of its cavity it being elliptical or oval the longer axis passing through the opening in the top of the socket. In connection with this socket is used a round headed screw so that the globe comes in contact with the head of the screw only.

The operation of this caster is similar to

that of the former. For heavy furniture in which casters of greater strength are to be used, I construct the globe with recesses over its surface the object being to give it a greater hold on the floor by increasing its surface of contact. The socket is or may be constructed in the same manner as the one hereinbefore described with the exception of the screw, which in this case, instead of being convex shaped at the head is provided with a cavity corresponding more or less with the convexity of the globe. It will be evident that the recessed portion of the globe has no bearing whatever in the socket, 60 while it affords an increased frictional hold on the floor particularly when carpeted.

In Fig. 4 the socket is cast around a screw having a flat steel head or a head hardened by temper. At a a depression is shown as 70 applied to the shank of the screw whereby it is prevented from turning within the socket.

The globe which may be made of metal, 80 steel, porcelain or glass bears against the head of the screw and has therefore but one point of contact. The cavity of the socket is moreover provided, in its upper portion, with a projecting rim which may be circular, oval, or polygonal, as shown in Figs. 85 5, 6, 7, which represent plan views of the cavity. The object of this rim is to facilitate the rotation of the ball or globe around its horizontal axis by applying a force of resistance created by friction on the one side 90 of the globe only while at the same time the opposite side is left entirely free and out of contact and thus acting on the ball with a leverage as it were to cause its rotation in any desired plane and thereby answering 95 the conditions of a caster in the most perfect manner.

It is evident from the above that the rim should be of such development or of such diameter as to allow the ball freely to play 100 within and to come in contact with the ball at one point thereof when motion is imparted to the piece of furniture that is provided with it.

The socket I prefer to make of two pieces 105 so as to enable any one to remove the ball for the purpose of cleaning or to substitute therefor another and lastly to securely confine the ball within the socket. For this purpose hooks or pins are cast to the upper 110 half and angular slots are cut in the lower part of the socket or cap piece. This mode

of fastening may be modified and constructed in different manners.

During the operation of this caster, dust, fibers of carpet etc. are carried along by the ball and produce the clogging up of the socket. To avoid this I cut a hole in the upper part of the socket and through it. By this means the dirt is worked out of the socket which is thereby preserved clean and

10 perfection of its operation secured.

When glass globes are used I prefer to remove the superficial glaze either by mechanical means *i. e.* by grinding them upon emery wheels or shaking the glass balls in 15 drums containing emery or by chemical means *i. e.* by dipping the balls in strong acid such as fluoric acid, in order to give more adhesion to the floor or carpet.

Having thus described my invention and 20 several modifications thereof I shall confine the claims of this application to the following:

1. In a socket the concavity of which is formed of an elliptical oval or other equiva-

lent form and the orifice or rim of which is 25 of a diameter smaller than that of the globe, whereby the globe may be inserted within the socket by the application of heat substantially as described.

2. In combination with the studs or pins 30 in the upper part of the socket, I claim the angular slot in the cap piece for the purposes described.

3. In combination with a socket cast in one piece with the screw or other appliance 35 for fastening the caster to a piece of furniture, I claim forming the concavity of an elliptical oval or other equivalent form whereby the globe will have but one point of contact within the socket which is diametrically opposite to its point of contact with the floor.

In testimony whereof I have hereunto subscribed my name.

EDWARD LINDNER.
